[57] CLAIM

The ornamental design for a flip up base for a cane, as shown and described.

DESCRIPTION

FIG. 1 is a top plan view of the novel flip up base for a cane;

FIG. 2 is a side elevational view thereof, the opposite side being a mirror image thereof shown with a outline of a cane for illustrative purposes only;

FIG. 3 is a bottom plan view thereof;

FIG. 4 is a front elevational view thereof; and,

FIG. 5 is a rear elevational view thereof.
